UNITED STATES PATENT OFFICE.

ABRAHAM TODD AND LEANDER H. MCKEE, OF CONSTANTIA, NEW YORK.

FIRE-ESCAPE.

SPECIFICATION forming part of Letters Patent No. 277,433, dated May 8, 1883.

Application filed February 10, 1883. (No model.)

To all whom it may concern:

Be it known that we, ABRAHAM TODD and LEANDER H. MCKEE, citizens of the United States, residing at Constantia, in the county 5 of Oswego and State of New York, have invented certain new and useful Improvements in Fire-Escapes; and we do hereby declare that the following is a full, clear, and exact description of the same, reference being had to the 10 annexed drawings, making a part of this specification, and to the letters and figures of reference marked thereon.

Figure 1 of the drawings is a view of a side elevation of our invention; Fig. 2, a sectional 15 view, showing the interior of the casing; and Fig. 3, a cross-section through line *xx*, Fig. 1.

This invention relates to certain new and useful improvements in that class of fire-escapes known as "frictional," the object thereof 20 being to produce such an escape as will be at once simple and inexpensive in its construction, effective in its operation, and readily attached to any window or like portion of a building.

25 The invention consists in the details of construction substantially as shown in the drawings, and hereinafter described and claimed.

In the accompanying drawings, A represents the casing, having openings *a* in each end 30 thereof, through which passes a rope, B, of any sufficient length, having at both extremities hooks *b* or other suitable means for attaching it to a window or like portion of a building. Upon the interior of this casing A 35 are suitably located trunnels C, around each of which is passed one turn of the rope B, said trunnels being firmly secured in place and prevented from turning by the ends *c* of the bails D, being bent in a right-angular direction and 40 passed through said trunnels and casing in opposing directions, thereby not only forming bearings for the trunnels, but at the same time bracing the casing and more securely sustaining any weight brought to bear upon the belt 45 E or its equivalent, suitably connected to the bails upon the outside of the casing for holding the person or persons in the act of descending from the building. A portion of the sides 50 of the casing is made removable, in order to admit of the adjustment of the rope upon the trunnels, and such examination of its interior as may be from time to time found necessary.

In the operation of our invention one end of the rope is connected to the windows or other like portions of a building and the belt 55 or its equivalent occupied by the person or persons to be lowered, the descent being regulated by grasping the rope below the casing and paying out said rope to suit his or their convenience, the trunnels in the casing over which 60 the rope passes preventing it from slipping too fast, and although we have shown but two such trunnels additional ones may be added, if found necessary, as the greater the number of trunnels the greater the resistance and consequent slowness of descent, with less strain 65 upon the operator's strength. After the casing has traveled the entire length of the rope and the operator landed upon the ground, should there be others to descend, the said rope and 70 casing, carrying the belt or its equivalent, are drawn up, the free end of the rope made fast, the already secured end disconnected, and the operation repeated, the ends of the rope and casing being simply reversed at each operation. 75

Having now fully described our invention, what we claim as new, and desire to secure by Letters Patent, is—

1. In a frictional fire-escape, the trunnels C, 80 located upon the interior of the casing A and held securely in place by means of the right-angular ends *c* of the bails D, passing through said casing and trunnels in an opposite direction, substantially as shown, and for the purpose described. 85

2. The casing A, constructed substantially as shown, and having its side or sides removable, in combination with the trunnels C, rope B, and bails D, connected to and passing 90 through the opposite sides of the casing and through the trunnels, substantially as and for the purpose set forth.

In testimony that we claim the above we have hereunto subscribed our names in the 95 presence of two witnesses.

ABRAHAM TODD.
LEANDER H. MCKEE.
